UNITED STATES PATENT OFFICE

JOHN HENDRIKSEN AND JOSEF HERAN, OF NEW YORK, N. Y.

DESIGN FOR A LAMP BASE OR SIMILAR ARTICLE

Application filed September 30, 1932. Serial No. 45,183. Term of patent 7 years.

To all whom it may concern:

Be it known that we, JOSEF HERAN, a citizen of Austria, and JOHN HENDRIKSEN, a citizen of Denmark, and both residing at 3310 Kossuth Ave., New York city, in the county of Bronx and State of New York, have invented a new, original, and ornamental Design for a Lamp Base or Similar article, of which the following is a specification, reference being had to the accompanying drawing, forming part thereof. The figure is a per-

spective view of a lamp base or similar article, showing our new design.

We claim:

The ornamental design for a lamp base or similar article substantially as shown.

Signed at New York city in the county of Bronx and State of New York this 16th day of October, A. D. 1932.

JOSEF HERAN.
JOHN HENDRIKSEN.
